H. LINDSAY.
SEAM FOR WOVEN WIRE FABRIC.
FILED MAR. 13, 1922.

FIG. 1

INVENTOR
Hamilton Lindsay,
By Davis & MacLean,
ATTORNEYS.

UNITED STATES PATENT OFFICE.

HAMILTON LINDSAY, OF CLEVELAND, OHIO, ASSIGNOR TO THE LINDSAY WIRE WEAVING COMPANY, OF CLEVELAND, OHIO, A CORPORATION OF OHIO.

SEAM FOR WOVEN-WIRE FABRIC.

Application filed March 13, 1922. Serial No. 543,247.

To all whom it may concern:

Be it known that I, HAMILTON LINDSAY, a citizen of the United States, residing at Cleveland, in the county of Cuyahoga and 5 State of Ohio, have invented a certain new and useful Improvement in Seams for Woven-Wire Fabric, of which the following is a full, clear, and exact description, reference being had to the accompanying drawings.

This invention relates particularly to a method of joining the ends of a wire fabric to form an endless belt. The belt so formed, which is particularly useful in Fourdrinier 15 paper machines, is also comprehended within my invention.

One of the difficulties encountered in lacing the ends of wire cloth so as to form an endless belt, has been the attainment of a 20 seam which possesses substantially the same construction as the remaining part of the cloth. Some forms of seam have embodied a diagonal stitch which fills up the interstices, thus rendering it difficult for water to pass 25 through the seam when the belt is in use. As a result the paper is weakened, on a line transversely thereof, each time the seam engages the pulp as it passes across the suction box.

30 Still another form of seam is embodied in a diagonal stitch which extends over two weft wires at each end of the belt and diagonally from one end across the joint to the other end, and then back and forth across 35 the fabric. In practice, this lacing is accomplished when the two end portions of the fabric are placed one on top of the other with the extreme end aligning, and when such belt is unfolded the space between the 40 severed warp threads is larger than the interstices of the fabric. This allows too much water to pass through the belt with a resultant detrimental effect upon the paper.

In order, therefore, to overcome the objectionable features above set forth, my invention 45 provides a method of joining the ends of wire cloth, so as to form a belt wherein the seam forms a mesh substantially the same as exists in the woven cloth. In addition, my invention contemplates the construction of a seam wherein sufficient space 50 is provided for water to pass through the belt so as not to weaken that portion of the paper, formed by the pulp adjacent the seam.

The means for carrying out my invention 55 will be fully set forth in the following description, which pertains to the drawings, and essential features will be summarized in the claims.

In the drawings, Fig. 1 is a plan view 60 of a portion of a finished belt having a seam made in accordance with my invention; Fig. 2 is a diagrammatic view showing the ends of the belt folded, one upon the other and indicating a method of lacing the ends 65 together; Figs. 3, 4 and 5 are end views of the folded belt indicating various steps in the method of forming the seam; and Fig. 6 is an end view showing the belt open.

My invention is concerned with a method 70 of forming a seam which is particularly adapted for wire belts which are used in the process of paper manufacture. Accordingly, in the embodiment shown, the ends of the fabric are indicated at A and B and as 75 being joined together with a binding thread or wire C. During the lacing operation, a filler thread or wire D is laid along the adjacent edges and is held thereagainst by the binding thread C. Then when the belt 80 is opened up, the filler lies intermediate the severed warp threads, as indicated in Figs. 1 and 6.

The various steps in forming the seam is 85 diagrammatically indicated in Figs. 2 to 5, wherein the end A is laid over the end B, so that the severed warp threads adjacent the respective ends are in substantially the same plane; then the filler D is laid along 90 the edges and sewed thereagainst by the binding thread C. In forming the seam, a customary spacing instrument E is inserted beneath the bights F which extend around the filler and is moved along the seam during 95 the lacing operation, thus leaving a space as indicated in Fig. 5. This space is just sufficient to permit the filler to lie flat intermediate the ends of the severed warp threads, as indicated in Figs. 1 and 6.

As illustrative of the method of lacing, 100 Fig. 3 shows the ends of the cloth in abutting engagement; Fig. 4 shows the filler and lacing instrument beneath the binding thread; and Fig. 5 shows the filler in position with the instrument removed. After 105 the seam is formed the belt is opened as indicated in Fig. 6, and the seam is then ironed flat.

By employing a filler thread intermediate the ends of the belt, the mesh of the cloth is maintained substantially uniform across the seam, and as a result, the paper formed by the pulp moving across the belt is of uniform quality. In addition, the filler permits the use of a diagonal stitch which has been found to withstand the wear occasioned by the movement thereof across the suction boxes of a Four-drinier machine. This type of stitching leaves the mesh of the belt on the adjacent seam comparatively open, thus allowing the uniform passage of water through the belt and insuring a uniform quality of paper.

Having thus described my invention, I claim:

1. A method of forming a seam on woven fabric comprising bringing the ends of the fabric together, laying a filler thread adjacent the ends and substantially in the same plane thereof and then lacing the filler to the ends of the web.
2. The method of forming a seam on a woven belt comprising bringing the ends of the severed warp threads adjacent each other, placing a filler thread transversely of the warp threads and then lacing the filler in such manner that when the ends are opened and the cloth laid flat the filler lies intermediate the severed warp threads, and substantially in the same plane as the weft threads.
3. A method of forming a seam on a woven wire belt comprising bringing the ends together so that the severed warp wires lie one above the other, placing a filler wire in abutting engagement with the severed

ends of the warp wires and then lacing the filler wire to the ends of the web.

4. The method for making a seam for woven wire belts comprising the placing of a filler wire intermediate the severed warp wires to be laced, whereby the mesh of the cloth adjacent the seam is substantially the same as the mesh of the fabric.

5. A seam for woven wire belts comprising in combination, a filler wire extending transversely of the belt, and a binding wire extending over and under said filler and through the ends to be joined.

6. A seam for woven belts comprising in combination a filler thread in abutting engagement with the severed warp threads to be joined, and a binding thread which extends diagonally between the ends to be joined and on both sides of the filler thread.

7. A seam for woven belts comprising in combination a binding thread which extends diagonally from one side of a seam to the other side thereof, and a filler thread extending transversely of the belt, said filler being held in substantially the same plane as the weft threads by the binding thread.

8. An endless belt comprising a strip of woven wire fabric and means joining the ends thereof together, said means comprising a filler wire in abutting engagement with the severed warp wires and a binding wire which extends diagonally between the ends to be joined and on both sides of the filler wire.

In testimony whereof, I hereunto affix my signature.

HAMILTON LINDSAY.
